UNITED STATES PATENT OFFICE.

ROBERT F. BURNS, OF ALBANY, NEW YORK.

IMPROVEMENT IN MACHINES FOR POLISHING THE EDGES OF BOOT AND SHOE SOLES.

Specification forming part of Letters Patent No. 97,758, dated December 14, 1869.

To all whom it may concern:

Be it known that I, ROBERT F. BURNS, of the city and county of Albany, State of New York, have invented a new and Improved Machine for Polishing the Edges of the Soles of Boots and Shoes; and I do hereby declare that the following is a full, clear, and exact description thereof, reference being had to the accompanying drawings, forming a part of this specification, in which—

Figure 1 represents a perspective view of the machine. Fig. 2 is a vertical view from above. Fig. 3 is a longitudinal vertical section. Fig. 4 is a front view of the machine. Fig. 5 is a cross-section of the polishing-wheel through red line in Figs. 2 and 3.

The polishing of the edges of the soles of boots and shoes is now generally performed by hand, and is very severe and laborious to the operator, and relatively slow when it is considered that most of the other operations and manipulations of the said articles are performed by machinery.

By my invention the edges of the soles of boots and shoes can be quickly polished, and with but little expense of time or strength, and uniform in appearance.

The nature of my invention consists in a polishing wheel or cylinder furnished on its periphery, at the edge of the face, with creasing projections, which produce contrary impressions on the edges of the soles near the upper, and is also furnished with grooves to receive and carry off the gummy matter that might accumulate in operating. The said cylinder is also heated with a gas-flame, back and within, which aids to finish and polish the edges of the leather. An adjustable gage is also provided, by which any required thickness of sole can be operated upon, which can be operated by means of a screw. Stops also are provided on the gage to receive the heel of the boot or shoe both at the commencement and the ending of an operation. The polishing-cylinder is carried by a shaft driven by a band-pulley, and the whole is supported in a suitable frame.

To enable others skilled in the art to make and use my invention, I will proceed to describe it in reference to the drawings and the letters of reference marked thereon, the same letters indicating like parts.

A, Figs. 1, 2, and 3, represents any suitable frame for supporting the several parts of the machine. B is an adjustable gage, furnished with female guides b b, into which the male guiding-pieces a a work. C is a bearing, holding a revolving nut, d, which nut is keyed or otherwise fastened to a hand-wheel, C, or its equivalent crank. f is a screw, made fixed at one end to the adjustable gage B, while the other end works into the revolving nut d. D is a polishing-cylinder, and may be made of iron, steel, or other suitable metal, and works under and partially into the adjustable gage B. The said cylinder is provided, at or near its face edge, with creasing projections s s. (Shown in Figs. 1 and 3.) It is also provided with grooves or recesses o o on its periphery, as shown in Figs. 1, 2, and 5. The said cylinder is carried by a suitable shaft, g, running in proper bearings h h, and driven by a band-wheel, E. Two notches or recesses, k k, are made into the adjustable gage, to act as stops or holding-lips for the heel of the article to be operated upon.

It is well known by all workers of leather that metal tools for embossing, creasing, or molding leather operate better when hot or warm than when cool.

In my invention I not only polish the main surface of the edges of the soles, but also crease or mold a bead on the edges of the same at or near the upper. This creasing or molding requires a greater and more efficient action of the tool; and as it is desirable that the molding be finished at the same time the polishing is done, I cause the projections s s to be heated to a higher temperature than the periphery of the cylinder D. To do this I make the cylinder with a solid face, connecting with and solid to the said periphery, and place the said projections s directly over the intersections of the angles of the face and said polishing-periphery. A jet of gas or other flame, G, is used within the said cylinder, and throws forward and impinges on the inside of the solid face, but not on the inside of the polishing-periphery. By this arrangement the face is heated by direct contact of the flame, and is kept at a higher temperature than the polishing-surface, which is heated only by radiation of the heat from the said flame G. The temperature of the polishing-surface proper is

also somewhat reduced by its rapid whirl, which fans the air and cools its surface, while the face of the wheel is less acted upon by its whirl, and becomes hotter, and communicates its heat to the projections *s*, which enables the molding to be performed at the same time the polishing is done.

I am aware that rotating cylinders heated by jets of gas-flame have been used; but they have been used with cylinders provided with polishing-surfaces only, and not with creasing projections *s*, or other milling or molding devices; and the flame used in those cases was not designed to give a varying temperature to the several portions of the cylinder to produce varying results, but was intended to result in a single and only one operation, while in my invention the edge is not only to be polished, but a bead is to be molded, which operations, when performed, require a varying temperature of the several parts to perfectly operate at one and the same time to effect the several results.

In operating with this machine the operator first adjusts the gage *B* to correspond with the thickness of the sole to be operated upon. This he does by operating the hand-wheel *C*, which will cause the revolving nut *d* to so affect the screw *f* as will cause it to throw the gage *B* toward or from the cylinder *D*, as may be required. The operator then grasps the boot or shoe to be operated upon, and holds it firmly, with the edge of the sole in contact with the periphery of the cylinder *D* and the bottom of the sole against the face of the gage.

B, and, commencing at one angle of the heel into one of the notches *k*, carries the edge of the sole past the shank, toward and around the toe, and thence on the opposite side to the opposite angle of the heel, which heel falls into the other notch *k*. When thus operated the projections *s* will make their proper impressions in the edge next to the upper, while the inclined recesses will receive and carry off the gummy matter which will exude from the leather in the operation.

Having described my invention, what I claim, and desire to secure by Letters Patent, is—

1. The polishing-cylinder *D*, when furnished with the creasing projections *s* and the inclined grooves *o*, substantially as and for the purpose set forth.
2. In combination with a polishing-cylinder, *D*, constructed with a solid face, and provided with creasing projections *s*, the jet of gas or other flame *G*, applied substantially as and for the purpose set forth.
3. The revolving nut *d*, screw *f*, hand-wheel *C*, in combination with the frame *A* and the adjustable gage *B*, substantially as and for the purpose set forth.
4. The stops *k*, made into and in combination with the adjustable gage *B*, substantially as and for the purpose set forth.

ROBERT F. BURNS.
